GLOVE

Filed June 5, 1926

Inventor
Robert E. Bolles
By his Attorney
A. V. Beeken

UNITED STATES PATENT OFFICE.

ROBERT E. BOLLES, OF WEST ISLIP, NEW YORK

GLOVE.

Application filed June 5, 1926. Serial No. 113,849.

This invention relates to gloves and has for its main objects and features the production of a glove, devoid of fastening means, that will wholly and completely 5 cover the palm of the hand while presenting a close-fitting and therefore neat appearance at the wrist portion and particularly at the top edge of the glove and that will accomplish these objects without waste of 10 material.

In the accompanying drawing the invention is embodied in a concrete and preferred form and shows a plan view of a glove blank or pattern illustrating my invention in 15 which

1 is the inner or front part of the glove and 1^a the outer or back part of the glove; 2 and 2^a are the usual finger pieces; 3 the usual thumb-piece socket; and 4 the inner 20 part of the thumb piece to which the outer thumb piece (not shown) is attached. 5 is the wrist portion of the glove and 6 the hand or body parts, 6^a indicating the palm portion and 6^b the back hand portion. The 25 dotted line 7 indicates the wrist line and 8 the line along which the glove blank is folded so that the part 1 will be superimposed upon the part 1^a and the finger pieces 2 superimposed each upon its complementary finger piece 2^a, the outer edges 9 of the blank being thus brought together and seamed to form the glove.

Heretofore in gloves where close-fitting hand and wrist portions were desired it has 35 been necessary, the hand being broader than the wrist, to slit the wrist from the top along a line extending well down into the palm of the hand to give sufficient vent to allow the wrist and hand portions to be drawn up 40 over the hand. The wrist portion is, when the glove is in position on the hand, then drawn closely about the wrist by overlapping the edges of the slit in the wrist and these edges are held in overlapped position 45 by fastening means. This style of glove has many objections: (a) it is difficult to provide fasteners that will withstand the strain exerted upon them while the glove is being worn and it is very often difficult when the 50 glove is on the hand to adjust the usual two-part fasteners now in common use to fastening position, thus causing the wearer more or less annoyance and discomfort in fastening the glove and also in keeping it 55 closed once it has been fastened; (b) the overlapping of the edges to produce a close

fit about the wrist very often distorts the seam along the outer side of the wrist portion; and (c) the palm or inside of the glove has an unsightly appearance in that 60 it is not feasible to extend the fasteners along the entire length of the slit and they are usually limited to the wrist portion of the slit, the consequent result being that that portion of the slit that extends down 65 into the palm produces a gaping effect that detracts from the neatness of the glove and exposes part of the palm of the hand to cold and dirt.

It has heretofore been attempted to obviate these difficulties and objections by eliminating the slit in the wrist portion, thus also eliminating the fastening means, and making the wrist portion of increasingly greater width as the top of the glove is approached so as to give sufficient room for the wrist portion to be drawn up over the hand. This results in a considerable amount of superfluous material in the wrist portion and produces quite a flare which 70 either hangs loosely from the wrist of the wearer or the useless, once the glove is on the hand, fullness at the wrist is gathered in by some confining means such as a strap or stitching. In either event, the appearance 75 is unsightly and detracts considerably from the desired and much-sought neatness in the fit of the glove. In addition to which there is considerable waste of material.

The glove of this invention is devoid of fastening means; and, in the present instance, the invention is embodied in the following form: The glove is so cut along the outer edges 9 of the blank that at a 80 point not substantially above the center, lengthwise of the palm, say y , there is an abrupt outward curve or flare, such curve gradually increasing in its progress toward the top edge 10 of the glove until at 100 a point above the wrist line 7, say x , it gradually begins to diminish so that as it nears the top edge 10 of the glove it describes substantially a straight line. In the glove of my invention there is a vertical slit, such as 105 11, extending downwardly from the top edge 10 of the glove to a point that stops short of the wrist line or of the hand portion 6 of the glove. By these means I provide a glove that wholly covers and protects the palm of 110 the hand; that is close fitting about the wrist and requires no fastening means; and yet

one that has sufficient vent to allow it to be easily drawn up over the heel or fleshy part of the hand. In such a glove there is no strain upon the seam along the edges 9 and 5 therefore no distortion of that line. There is substantially no superfluous fullness at the wrist and therefore the usual slovenly appearance of the ordinary "slip-on" glove when on the hand is avoided; and, there 10 being no strain on the wrist portion, the slit 11 remains, when the glove is on the hand, substantially closed. As there is no "flare cuff" or "cape" or "gauntlet" effect at the wrist, the glove is as applicable to men's 15 as to women's wear and lends itself readily to the "mannish" styles so much in vogue. It is obvious that there is considerable saving in the amount of material used in a glove so made as compared with the material used in 20 the usual "slip-on" glove.

I claim:

1. A glove with a substantially close-fitting non-elastic wrist portion and devoid of fastening means bounded in part on the outer 25 or seam side of the glove by an irregular curve beginning abruptly at a point not substantially above the center, lengthwise, of the palm and continuing in the direction of the top of the glove first in a gradually increasing 30 and then in a gradually diminishing curve and terminating at the top of the glove, said wrist portion being provided with a vertical slit substantially coextensive with the length thereof and extending downwardly from the top of the glove.

2. A glove with a substantially close-fitting non-elastic wrist portion and devoid of fastening means bounded in part on the outer or seam side of the glove by an irregular 40 curve beginning abruptly at a point not substantially above the center, lengthwise, of the palm and continuing in the direction of the top of the glove first in a gradually increasing and then, when a point above the 45 wrist line is reached, in a gradually diminishing curve and terminating at the top of the glove, said wrist portion being provided with a vertical slit substantially coextensive with the length thereof and extending downwardly from the top of the glove.

50

3. A glove adapted to provide without the aid of fastening means a substantially close-fitting non-elastic wrist portion, said glove being provided with a vertical slit in said wrist portion extending downwardly toward the palm but terminating at a point short of the hand, the glove being bounded by a seam, at the outer side thereof, that follows a line which, at a point along the side of the hand, suddenly curves outwardly and, continuing in the direction of the wrist in an irregular flat curve, gradually becomes substantially straight, and terminates at the top edge of the glove.

65

4. A glove, having a hand portion and a substantially close-fitting non-elastic wrist portion and devoid of fastening means, bounded in part, at the seam or outer side of the glove, by an outward curve abruptly beginning at a point not substantially above 70 the center, lengthwise, of the palm and gradually increasing in the direction of the top of the glove until a point above the wrist line is reached when the curve gradually decreases until it eventually becomes a substantially 75 straight line terminating at the top edge of the glove, said wrist portion having a vertical slit extending downwardly from the top edge of the glove to a point short of the wrist line.

80

5. A glove, having a hand portion and a substantially close-fitting non-elastic wrist portion and devoid of fastening means, bounded in part, at the seam or outer side of the glove, by an outward curve abruptly 85 beginning at a point not substantially above the center, lengthwise, of the palm and gradually increasing in the direction of the top of the glove until a point above the hand portion is reached when the curve gradually 90 decreases until it eventually becomes a substantially straight line terminating at the top edge of the glove, said wrist portion having a vertical slit substantially coextensive with the length thereof extending downwardly 95 from the top of the glove.

Signed at New York city, in the county of New York and State of New York, this 4th day of June, 1926.

ROBERT E. BOLLES.

one that has sufficient vent to allow it to be easily drawn up over the heel or fleshy part of the hand. In such a glove there is no strain upon the seam along the edges 9 and therefore no distortion of that line. There is substantially no superfluous fullness at the wrist and therefore the usual slovenly appearance of the ordinary "slip-on" glove when on the hand is avoided; and, there being no strain on the wrist portion, the slit 11 remains, when the glove is on the hand, substantially closed. As there is no "flare cuff" or "cape" or "gauntlet" effect at the wrist, the glove is as applicable to men's 15 as to women's wear and lends itself readily to the "mannish" styles so much in vogue. It is obvious that there is considerable saving in the amount of material used in a glove so made as compared with the material used in 20 the usual "slip-on" glove.

I claim:

1. A glove with a substantially close-fitting non-elastic wrist portion and devoid of fastening means bounded in part on the outer 25 or seam side of the glove by an irregular curve beginning abruptly at a point not substantially above the center, lengthwise, of the palm and continuing in the direction of the top of the glove first in a gradually increasing 30 and then in a gradually diminishing curve and terminating at the top of the glove, said wrist portion being provided with a vertical slit substantially coextensive with the length thereof and extending downwardly from the top of the glove.

2. A glove with a substantially close-fitting non-elastic wrist portion and devoid of fastening means bounded in part on the outer or seam side of the glove by an irregular 40 curve beginning abruptly at a point not substantially above the center, lengthwise, of the palm and continuing in the direction of the top of the glove first in a gradually increasing and then, when a point above the 45 wrist line is reached, in a gradually diminishing curve and terminating at the top of the glove, said wrist portion being provided with a vertical slit substantially coextensive with the length thereof and extending downwardly from the top of the glove.

3. A glove adapted to provide without the aid of fastening means a substantially close-fitting non-elastic wrist portion, said glove being provided with a vertical slit in said wrist portion extending downwardly toward the palm but terminating at a point short of the hand, the glove being bounded by a seam, at the outer side thereof, that follows a line which, at a point along the side of the hand, suddenly curves outwardly and, continuing 60 in the direction of the wrist in an irregular flat curve, gradually becomes substantially straight, and terminates at the top edge of the glove.

4. A glove, having a hand portion and a substantially close-fitting non-elastic wrist portion and devoid of fastening means, bounded in part, at the seam or outer side of the glove, by an outward curve abruptly beginning at a point not substantially above 70 the center, lengthwise, of the palm and gradually increasing in the direction of the top of the glove until a point above the wrist line is reached when the curve gradually decreases until it eventually becomes a substantially 75 straight line terminating at the top edge of the glove, said wrist portion having a vertical slit extending downwardly from the top edge of the glove to a point short of the wrist line.

5. A glove, having a hand portion and a substantially close-fitting non-elastic wrist portion and devoid of fastening means, bounded in part, at the seam or outer side of the glove, by an outward curve abruptly 85 beginning at a point not substantially above the center, lengthwise, of the palm and gradually increasing in the direction of the top of the glove until a point above the hand portion is reached when the curve gradually 90 decreases until it eventually becomes a substantially straight line terminating at the top edge of the glove, said wrist portion having a vertical slit substantially coextensive with the length thereof extending downwardly 95 from the top of the glove.
